GOLF PUTTER HEAD

Melvin Paynor, Providence, R. I.

Application April 17, 1952, Serial No. 19,363

Term of patent 3½ years

(Cl. D34—5)

To all whom it may concern:

Be it known that I, Melvin Paynor, a citizen of the United States of America, residing at Providence, in the county of Providence, and State of Rhode Island, have invented a new, original, and ornamental Design for a Golf Putter Head, of which the following is a specification, reference being had to the accompanying drawing, forming part thereof.

Figure 1 is a perspective view of a golf putter head, showing my new design.

Fig. 2 is a front elevational view of the putter head.

Fig. 3 is an end elevational view of the putter head.

Fig. 4 is a plan view of the putter head.

I claim:

The ornamental design for a golf putter head, as shown.

MELVIN PAYNOR.
